Primary Examiner — John Windmuller*Assistant Examiner* — John R Yeh(74) *Attorney, Agent, or Firm* — Stephen D. Carver**CLAIM**

The ornamental design for a cap clip, as shown and described.

DESCRIPTION

FIG. 1 is a frontal isometric view of a cap clip showing my new design in use;

FIG. 2 is an enlarged frontal isometric view thereof;

FIG. 3 is an enlarged rear isometric view thereof;

FIG. 4 is a front elevational view thereof;

FIG. 5 is a rear elevational view thereof;

FIG. 6 is a right side view thereof;

FIG. 7 is a left side view thereof;

FIG. 8 is a top plan view thereof; and,

FIG. 9 is a bottom plan view thereof.

The broken lines in the Figures represent environment and form no part of the claimed design.

1 Claim, 6 Drawing Sheets(56)
